UNITED STATES PATENT OFFICE.

RALLSTON M. SHERMAN, OF GLASTONBURY, CONNECTICUT, ASSIGNOR TO SILENT GLOW OIL BURNER CORPORATION, OF HARTFORD, CONNECTICUT, A CORPORATION OF CONNECTICUT.

VAPOR BURNER.

Application filed August 25, 1926. Serial No. 131,397.

My invention relates to the class of burners above mentioned and more especially designed for the burning of oil, and an object of my invention, among others, is the production of a burner of this class that shall be simple in construction and particularly efficient in operation.

One form of a burner embodying my invention, and in the construction and use of which the objects herein set out, as well as others, may be attained, is illustrated in the accompanying drawings in which—

Figure 1 is a view in side elevation of my improved burner.

Figure 2 is a similar view, but looking from a point at right angles to the point of view of Figure 1, the perforations in the wall of one case being only partially shown in these figures.

Figure 3 is a top view of my improved burner.

Figure 4 is a top view of the burner base.

Figure 5 is a view in central vertical section through my improved burner.

Figure 6 is a fragmental view showing a slightly different form of the burner.

In the accompanying drawings the numeral 6 indicates a base supported on a leg 7 at one end and on adjusting screws 8 at the opposite end, these screws being employed as a means for leveling the device as a whole. A tubular support 9 rises from the base, and receives a post 10 that is adjustably secured as by means of a screw 11. A burner base 12 is secured to the upper end of the post 10, as by means of screw threaded engaging parts.

Said base supports two burners, in the construction herein shown, both of these burners being of similar construction, and the description thereof will therefore be confined to a single burner. A fuel groove 13 is formed in the base, extending completely around it, and this groove is supplied with fuel through a supply pipe 14, there being two of these supply pipes connected with a common supply pipe 15 and extending horizontally therefrom and then upwardly to the burner, as shown in Fig. 2 of the drawings. Flow of fuel through each supply pipe may be controlled as by means of a valve 16, and each supply pipe may be provided with a drip cup 17.

A vapor groove 18 is also formed in the

base concentric with the fuel groove, and ducts 19 extend from the fuel groove to the vapor groove, there being four of these ducts in the construction herein shown, and these ducts open out of the fuel groove at a point above the bottom of said groove so that fuel will not flow from the fuel to the vapor groove. A result of this construction is that vapor is formed in the oil groove and rises upwardly therefrom, said vapor also passing through the ducts 19 into the vapor grooves and the latter therefore receives nothing but vapor. The flow of oil to the groove 18 may be regulated by valves as shown, or otherwise, to an amount substantially not greater than the amount consumed and vaporized in the grooves 13 and 18, thereby preventing flow of oil through the ducts 19. Vapor only, therefore, will exist and be ignited in the combustion chamber 28 supplied from the groove 18.

By reason of the fact that these grooves extend around the burner, it is essential that the level of the oil within the grooves 13 shall be the same at all points in order to prevent such oil from passing through any of the ducts 19 into the vapor groove 18.

Flanges 20—21—22 and 23 are concentrically formed on the base, rising therefrom, and shells or cases 24—25—26 and 27 are formed to fit said flanges, and said shells extend upwardly therefrom forming combustion chambers 28—29. An opening 30 within the case 27 is closed at its top by a cap 31, and the space between the shells or cases 25—26 is closed at the top by a ring 32. The walls of the cases 24 and 27 are provided with perforations 33 throughout their entire surface, a portion only of said perforations, however, being shown in the drawings herein.

In that form of the structure shown in Fig. 6 the burner base 12 has the supply pipe 14, as described with respect to the device hereinbefore set forth, and it also has a vapor groove 18 with a duct or ducts 19 extending from the vapor groove to a fuel groove 34. This structure is similar to that hereinbefore described, with the exception that this fuel groove is wider and deeper with respect to the vapor groove than is the groove shown in the device of the preceding figures.

In accordance with the provisions of the patent statutes I have described the princi-

ples of operation of my invention, together with the device which I now consider to represent the best embodiment thereof; but I desire to have it understood that the device shown is only illustrative and that the invention may be carried out by other means and applied to uses other than those above set out.

I claim—

10. 1. A burner including a burner base having therein a fuel groove, a vapor groove to receive for ignition therein vapor from said fuel groove, a duct communicating with both of said grooves and located above the bottom of the fuel groove to effect flow of vapor only to the vapor groove under normal operation of the burner, a combustion chamber opening from each of said grooves, and means for supplying fuel to the fuel groove.
15. 2. A burner including a burner base hav-

ing therein a circular fuel groove, a concentric vapor groove to receive vapor from said fuel groove, a duct communicating with and located above the bottom of both of said grooves to effect flow of vapor only to the 25 vapor groove under normal operation of the burner, a combustion chamber opening from each of said grooves, and means for supplying fuel to the fuel groove.

3. A burner including a base having there-
in a vapor groove, a fuel groove deeper and
wider than said vapor groove and surround-
ed by the latter, a duct communicating with
said grooves and located above the bottoms
thereof, to conduct vapor only to said vapor 35
groove, a combustion chamber for each of
said grooves, and means for supplying fuel
to the fuel groove.

RALLSTON M. SHERMAN.
